UNITED STATES PATENT OFFICE.

GEORGE G. JONES, OF CLEVELAND, OHIO.

DESIGN FOR A COMBINED GRAVE MARKER AND FLAG HOLDER.

Application filed November 30, 1921. Serial No. 519,014. Term of patent 7 years.

To all whom it may concern:

Be it known that I, GEORGE G. JONES, a citizen of the United States, residing at Cleveland, in the county of Cuyahoga and State of Ohio, have invented a new, original, and ornamental Design for a Combined Grave Marker and Flag Holder, of which the following is a specification, reference being had to the accompanying drawings, forming a part thereof.

Figure 1 is a view of the obverse side of a combined grave marker and flag holder made in accordance with my design and Fig. 2 is a view of the reverse side.

I claim:

The ornamental design for a combined grave marker and flag holder substantially as shown in the drawings hereof.

GEORGE G. JONES.
